JOHN KARMAZIN, OF EAST ELMHURST, NEW YORK

RADIATOR

Application filed May 28, 1923. Serial No. 641,850.

This invention relates to radiators suitable for use in connection with internal combustion engines using cooling water.

Radiators for water cooled internal combustion engines require the passage of water in one direction through one set of passages and the passage of air through other passages in another direction. For high efficiency it is desirable to have low resistance to air-flow and also to flow of water, and yet to divide up the water-flow and air-flow into sufficiently small streams so that the water may be cooled rapidly, the heat being conducted to the air through thin metallic walls. It is also of great importance that every part of the radiator be active in dissipating this heat.

There are two principal types of radiators, one the honeycomb type of radiator, made up of corrugated sheet metal strips suitably spaced apart to form corrugated conduits for the water, the other being the fin-and-tube type made up of a number of spaced apart flat sheets of metal through which are passed a number of tubes to conduct the cooling water. The assembling of this form of radiator has contributed considerably to its cost.

The present invention relates to a radiator which, insofar as appearance and operation are concerned, resembles the fin-and-tube type, but which is made up in an entirely different manner, by which the expense of assembly is very materially reduced.

An object of the present invention is to provide an improved radiator wherein parts may be readily brought together and assembled into a cooling section and thus into a complete radiator in an inexpensive and expeditious manner.

Another object of the invention is to provide a radiating section in which the use of solder may be, to a large extent, rendered unnecessary in making the conduits watertight.

Another object of the invention is to provide a radiating section in which water conduits are integral with their supports whereby there is a rapid transfer of heat energy from the tube to the surrounding air.

Another object of the invention is to provide a radiator wherein a damaged part of

the cooling section may be readily removed and new parts substituted.

Other objects of the invention will be apparent as the invention is described in detail below.

In the accompanying drawings there is shown, for the purpose of illustrating the invention, a completed radiator made in accordance with the present invention, together with several modified forms of radiator elements which may be used in accordance with the present invention. In the accompanying drawings:

Fig. 1 is a front view of a complete radiator according to my invention;

Fig. 2 is a horizontal section taken on the line 2-2 of Fig. 1;

Fig. 3 is a vertical section taken on the line 3-3 of Fig. 1;

Fig. 4 shows a method of fastening the sections together;

Fig. 5 is a plan view of a portion of one form of radiator element;

Fig. 6 is a plan view of a modified form of the element;

Fig. 7 shows a detail of a slightly further modified form of element;

Fig. 8 is a section showing the assembly of a number of elements and taken on the line 8-8 of Fig. 6;

Figs. 9 and 9A illustrate further modifications of the element.

Figs. 6, 7 and 8 illustrate a completed strip or element of material. It will be seen that the strip 60 has a number of regularly-spaced 85 depending tubes 61, and holes 62 intermediate the tubes 61. The severed material has been bent down to provide fins or deflectors 63 or 63^a (Fig. 7). The tubes 27 are given a slight taper, and, if desired, the punch and die mechanism may be such as to give the tubes an intermediate shoulder such as shown at 64 and a smaller inwardly directed ledge 65 at the bottom end of the tube. It is preferable to locate the shoulder 64 half-way between the ledge 65 and the upper surface 66, for then the tubes reinforce one another.

Fig. 8 shows the way of assembling elements such as above described into a cooling section. The strip of metal with the tubes 100

and with or without the additional punchings is cut into pieces of the proper length, and these pieces are superimposed on one another to bring the tubes 61 into the open 5 or wider end of the corresponding tubes of the adjacent element. In this manner one can readily build up a cooling section of any desired height or width, and one finds a plurality of tubes 67 extending from the top 10 to the bottom of the cooling section. Where the material is deformed to provide the fins or deflectors, these deflectors will operate to stir the air passing through the cooling section so as to bring it into intimate contact 15 with the outside of the tubes.

The structures heretofore disclosed have contemplated the use of round tubes, but the configuration of the tube is not essential, as shapes other than round may be used. Two 20 such shapes are shown in Figs. 9 and 9^A in which the tubes 68 and 69 are oblong in shape. They may be made up in a manner similar to the method described with respect to the round tubes.

25 The cooling section which has been made up in the manner above described is now ready to be placed in a frame to make up a finished radiator. One form of such a radiator will now be described. A strip of 30 metal 170, suitably punched, is placed between the upper two of the nested elements, and to this strip may be fastened the upper tank 171. A lower tank 172, with suitably located apertures in the upper part thereof, 35 is passed over the projecting tubes 174 of the bottom section. A very convenient method of fastening these parts together is shown in Fig. 4, according to which rods 175 are passed down through two or more of the 40 tubes 67 and soldered in place as shown at 177. The soldering of these rods at both top and bottom to the upper and lower elements of the cooling section permanently fasten together all parts of the cooling section. 45 In order to protect the projecting ends 178 of the elements of the cooling section, there may be provided, if desired, a strip 179, to which the ends 178 may be soldered. A suitable frame 180 may be provided, to give the 50 radiator a finished appearance; and to make the structure more rigid, brackets 181 and 182 are used, reaching from the tanks to reinforce the cooling section.

Sometimes it is desirable to remove excess 55 metal; and then one can punch holes between the tubes 27 as shown at 27^A in Figure 5.

Radiators made up in accordance with the present invention have been found to be a distinct advance in the art, on account of the 60 use of the same piece of metal to act as a conduit for the water and as one side of an air conduit or channel. One is able to use the metal at highest efficiency in transferring heat from the water to the air. One is able 65 to cool an automobile engine with a much

smaller number of tubes or with a much smaller radiator than is possible in the ordinary fin-and-tube type of radiator, in which the metallic parts cannot be brought into good thermal contact. As the use of solder 70 is not necessary to make the device watertight, it is of course obvious that the troubles incident to soldering have been eliminated, and the elimination of these soldered joints makes it possible to readily take the radiator 75 apart for purposes of repairs, replace the worn elements with new ones, and restore it to service.

What is claimed is:

1. A cooling section for radiators comprising a plurality of superimposed elements each having a plurality of rows of integral transverse tubes, the tubes of one element being nested into the tubes of an adjacent element, and rods passed through certain 80 of the tubes and fastened to the outside elements by soldering to the tubes thereon.

2. A cooling section for radiators comprising a plurality of superimposed elements each having a plurality of rows of integral 90 transverse tubes provided with intermediate shoulders, the tubes of one element being nested into the tubes of an adjacent element, the shoulders spacing the elements, and rods passed through certain of the tubes and fastened to the outside elements by soldering to the tubes thereon.

3. A cooling section for radiators comprising a plurality of superimposed elements each having a plurality of integral transverse tubes, the tubes of one element being nested into the tubes of an adjacent element, and rods passed through certain of the tubes, and fastened to the outside elements by soldering to the tubes thereon, combined with 10 water tanks opening into the tubes.

4. A cooling section for radiators comprising a plurality of superimposed elements each having a plurality of rows of integral transverse tubular projections, the tubular projections of one element being nested into the tubular projections of an adjacent element to form continuous tubes, means for securing said elements together comprising rods passing through certain of said tubes and 11 soldered to the tubular projections of the outside elements, and strips fastened to the ends of said elements.

JOHN KARMAZIN.
